DESIGN FOR A COFFEE DISPENSER OR SIMILAR ARTICLE

Charles Stern, Jersey City, N. J.

Application February 21, 1946, Serial No. 126,817

Term of patent 3½ years

(Cl. D52—2)

To all whom it may concern:

Be it known that I, Charles Stern, a citizen of United States, residing at Jersey City, in the county of Hudson and State of New Jersey, have invented a new, original, and ornamental Design for a Coffee Dispenser or Similar Article, of which the following is a specification, reference being had to the accompanying drawing, forming part thereof.

In the drawing

Fig. 1 is a front view of a coffee dispenser or similar article, showing my new design;

Fig. 2 is a side view thereof;

Fig. 3 is a rear view thereof;

Fig. 4 is a bottom view thereof; and

Fig. 5 is a cross-sectional view taken on line 5—5 of Fig. 3.

I claim:

The ornamental design for a coffee dispenser or similar article, as shown.

CHARLES STERN.
